UNITED STATES PATENT OFFICE

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY

ROTATION MECHANISM FOR ROCK DRILLS

Application filed January 12, 1928. Serial No. 246,231.

This invention relates to rock drills, but more particularly to rotation mechanism for fluid actuated rock drills of the hammer type.

The objects of the invention are to impart rotary movement to the drill steel between successive blows of the hammer piston and to effect a prompt and positive engagement and instant release between the rotary and fixed elements of the rotation mechanism.

10 Other objects will appear hereinafter, and to all of these ends the invention consists of the combination of elements and arrangement of parts having the general mode of operation substantially as hereinafter described and 15 claimed and illustrated in the accompanying drawings, in which

Figure 1 is a sectional elevation of a rock drill having the invention applied thereto,

Figure 2 is a transverse view taken through 20 Figure 1 on the line 2—2 looking in the direction indicated by the arrows,

Figure 3 is a view similar to Figure 2, taken on line 3—3 of Figure 1,

Figure 4 is a perspective view of the rotation cover, and

Figure 5 is a perspective view of the rotation cup.

Referring to the drawings, the invention is shown embodied in a rock drill having a cylinder A provided with a hammer piston B reciprocable in the cylinder for delivering 30 blows of impact to a working implement (not shown) extending into the front end of the rock drill.

35 On the rearward end of the cylinder A is disposed a back cylinder C having a hollow extension D which projects into the cylinder A to guide the hammer piston B. The rearward end of the back cylinder C acts as a seat for a rotation ring E and on the rotation ring E is seated a back head F which forms a cover for the rearward end of the drill.

The cylinder parts A and C, the rotation ring and the back head F may be held in operative position in any suitable manner, as for instance, by the side bolts G disposed on opposite sides of the drill.

Pressure fluid for actuating the drill may be conveyed from a suitable source of supply (not shown) by a connection H attached to

the back head F. A passage J formed in the back head F, the rotation ring E and the back cylinder C conveys the pressure fluid from the connection H to a throttle valve K in the back cylinder C. The throttle valve K may be of a well known type and is adapted to control the admission of pressure fluid into the back cylinder C where it may be distributed by the piston B in a well known manner.

Suitable means are provided for imparting a step by step rotative movement to the working implement preparatory to the delivery of the blow of the hammer piston thereto. To that end a fluted rifle bar L which is journaled in the back head F at one end and also in the back cylinder C extends through the said back cylinder and interlocks slidably with a fluted rifle nut O in the rearward end of the piston B. Near the rearward end of the rifle bar L is a cam P in the form of a parallelogram having two long straight sides Q and end surfaces R inclined with respect to the sides Q but parallel with respect to each other.

The cam P lies within the rotation ring E and is encircled by a cup S which seats with its front end on the back cylinder C and with its rearward end on the back head F. The cup S is adapted to rotate in the rotation ring and has a central aperture T in its front end to rotatably receive the rifle bar L.

A closure is provided for the rearward end of the cup S in the form of a cover U which has a cylindrical body portion V adapted to fit snugly in the rearward end of the cup S. In order to prevent rotation of the cover U with respect to the cup S, said cover is provided with a pair of diametrically opposed wings W which in the assembled position seat into notches X in the rearward end of the cup S. In the peripheries of the cup S and the cover U are formed longitudinal slots Y and Z respectively which in the assembled position of these elements will be in alignment with each other to serve as guides for rollers b adapted to be pressed between the end surfaces R of the cam and the wall of the cup S. The cover U also has a central aperture c to receive the rearward end of the rifle bar L for which it forms a bearing.

In order that only limited rotative movement may occur between the cup S and the cam P, thus at all times assuring the correct relative positions of the cam and the rollers, the cover U is provided with integral lugs d on one side thereof to extend into the cup S to a point near the bottom of said cup. The outer surfaces e of the lugs d are suitably curved to correspond to the inner surface of the cup against which they seat for preventing relative transverse movement between the cover U and said cup, and also to prevent flexion of the lugs when subjected to the thrust of the cam P.

On the inner sides of the lugs d are diverging surfaces f and g to act as stops for limiting rotative movement of the cam P with respect to the cup S. Preferably the angle of divergence is only of such extent as to permit of only sufficient rotation of the cam P within the cup S to enable the rollers b to be released from the rotation ring E.

The diverging surfaces f and g form apices h at the point of divergence and these apices h may be spaced with respect to each other a distance equalling substantially the width of the cam P between the straight sides Q. By thus permitting the lugs d to contact with the cam P at this point, said lugs may assist materially in maintaining the rifle bar L in coaxial alignment with the cylinder after the parts become worn due to usage.

The slots Y and Z wherein the rollers b are disposed are preferably only of slightly greater depth than the diameters of the rollers b and only of slightly greater width than the rollers so that the rollers will at all times lie in planes substantially parallel to the axis of rotation. In this way the rollers will be held against tilting with respect to the rotation ring E which they are adapted to engage and will therefore at all times remain in the correct position so that a maximum area of contact may be maintained between these elements, and also to assure against the possibility of only one roller being clamped between the cam and the rotation ring.

During the operation of the device, as the piston starts rearwardly from the position illustrated in Figure 1, a slight rotative movement is imparted to the rifle bar L at the instant of reversal of the piston and thus also to the cam P. This is due to the interlocking spiral flutes of the rifle bar and the rifle nut O, since, as will be readily understood, the piston tends to move in a straight line. As a result of such rotative movement of the rifle bar the rollers b will be pressed in a radial direction firmly against the wall of the rotation ring E thus preventing any further rotative movement of the rifle bar during this stroke of the piston. By holding the rifle bar against rotation, the piston B will describe a partial revolution on the rifle bar and, be-

ing slidably interlocked with the drill steel through suitable chuck mechanism (not shown), such rotative movement of the piston will be transmitted through the connecting elements to the drill steel to change the position of the drill steel in the drill hole for the succeeding forward stroke of the piston.

After the piston reaches its rearward limit of travel and at the instant of its reversal the rifle bar L will be sufficiently rotated by the piston to enable the cam P to release the rollers b. This will enable the rifle bar L to rotate relatively to the piston B and thus avoid any friction between the stationary and movable elements of the rotation mechanism which might otherwise hinder the speed of the piston.

I claim:

1. In a rock drill having a cylinder and a piston, rotation mechanism for the piston comprising a rotation ring, a rifle bar extending through the ring into the cylinder to interlock slidably with the piston, a cup rotatable in the ring and having longitudinal slots in its periphery, rollers in the slots, a cam on the rifle bar to press the rollers against the rotation ring and hold the rifle bar against rotation, thus causing partial rotation of the piston relatively to the rifle bar, a cover for the cup having an aperture to guide one end of the rifle bar, lugs integral with the cover and extending into the cup on opposite sides of the cam, diverging surfaces on the inner sides of the lugs to permit limited relative rotative movement between the cam and the cup, and seating surfaces on the lugs bearing against the inner surface of the cup to prevent flexion of the lugs.

2. In a rock drill having a cylinder and piston, rotation mechanism for the piston comprising a rotation ring, a rifle bar extending through the ring into the cylinder to interlock slidably with the piston, a cup rotatable in the ring and having longitudinal slots in its periphery, rollers in the slots, a cam on the rifle bar to press the rollers against the rotation ring for holding the rifle bar against rotation, thus causing partial rotation of the piston relatively to the rifle bar, a cover interlocked with the cup forming a bearing for one end of the rifle bar, lugs integral with the cover extending into the cup on opposite sides of the cam, diverging surfaces on the inner side of the lugs to permit limited relative rotative movement between the cam and the cup, and apices formed by said surfaces abutting the sides of the cam to prevent relative transverse movement between the cam and the cup.

In testimony whereof I have signed this specification.

GEORGE W. HULSHIZER.
